UNITED STATES PATENT OFFICE

148,195

DESIGN FOR A BATHTUB

Juan Springwell, Chicago, Ill., assignor to Sears, Roebuck and Co., Chicago, Ill., a corporation of New York

Application August 31, 1946, Serial No. 133,001

Term of patent 14 years

(Cl. D4—4)

To all whom it may concern:

Be it known that I, Juan Springwell, a citizen of the United States and a resident of Chicago, in the county of Cook and State of Illinois, have invented a new, original, and ornamental Design for a Bathtub, of which the following is a specification, reference being had to the accompanying drawing, forming a part thereof.

Fig. 1 is a top plan view of a bathtub embodying my new design; and

Fig. 2 is a perspective view of the same.

The end and back not seen in the drawings are plain.

I claim:

The ornamental design for a bathtub, as shown and described.

JUAN SPRINGWELL.
